UNITED STATES PATENT OFFICE.

RUDOLF WEIGANG, OF BAUTZEN, GERMANY, ASSIGNOR TO CARL O. v. KÖKERITZ, OF MOUNT VERNON, NEW YORK.

DESIGN FOR A LABEL-BLANK.

41,837.

Specification for Design.

Patented Oct. 10, 1911.

Application filed June 9, 1911. Serial No. 632,250. Term of patent 3½ years.

To all whom it may concern:

Be it known that I, RUDOLF WEIGANG, a subject of the Emperor of Germany, residing at 4 Wallstrasse, Bautzen, Saxony, Germany, have invented a new, original, and ornamental Design for Label-Blanks, of which the following is a specification, reference being had to the accompanying drawing, forming part thereof.

The figure is a plan view of a label blank, showing my new design.

I claim:

The ornamental design for a label blank, as shown.

RUDOLF WEIGANG.

Witnesses:

GEORG LANGE,
ERNST HARTWIG.
